UNITED STATES PATENT OFFICE.

THOMAS A. SHANLEY, OF MERIDEN, CONNECTICUT, ASSIGNOR TO INTERNATIONAL SILVER CO., OF MERIDEN, CONNECTICUT, A CORPORATION OF NEW JERSEY.

DESIGN FOR A GLASS VESSEL OR SIMILAR ARTICLE.

51,938.

Specification for Design.

Patented Apr. 2, 1918.

Application filed January 12, 1918. Serial No. 211,683. Term of patent 7 years.

To all whom it may concern:

Be it known that I, THOMAS A. SHANLEY, a citizen of the United States, residing at Meriden, in the county of New Haven and State of Connecticut, have invented a new, original, and ornamental Design for a Glass Vessel or Similar Article, and do hereby declare the accompanying drawing to be a full, clear, and exact illustration of the same, and which said drawing constitutes part of

this application and represents in a perspective view a glass vessel or similar article embodying my design.

I claim:

The ornamental design for a glass vessel or similar article, as shown.

THOMAS A. SHANLEY.

Witnesses:

HENRY J. MARTIN,
FRANK H. CUSHING.
